UNITED STATES PATENT OFFICE.

ARTHUR V. DA COSTA, OF PROVIDENCE, RHODE ISLAND.

TOY.

1,394,669.

Specification of Letters Patent.

Patented Oct. 25, 1921.

Application filed February 18, 1921. Serial No. 446,128.

To all whom it may concern:

Be it known that I, ARTHUR V. DA COSTA, a citizen of the United States, residing at Providence, in the county of Providence and State of Rhode Island, have invented certain new and useful Improvements in Toys, of which the following is a specification.

This invention relates to improvements in the construction of toys, and has for its 10 object to provide an animated toy having a bulbous body member having a head member supported to roll about upon its upper surface, when agitated, to produce a life-like effect, said head member being provided with 15 means for returning it to an upright position after having been moved from such position and the body member also being provided with a weight near its bottom portion for the purpose of returning it together with 20 its head member back to normal after having been moved from upright position.

With these and other objects in view, the invention consists of certain novel features of construction, as will be more fully described, and particularly pointed out in the appended claims.

In the accompanying drawing:

Figure 1 is an elevation illustrating one form of toy which may be made by my improved construction.

Fig. 2 is a sectional elevation illustrating the mechanism by which the head member may be rolled about upon the body member, and returned to upright position thereon 35 also showing the weight for returning the body member and its head member to normal upright position after having been moved therefrom.

Fig. 3 is a perspective view of the head 40 balancing rod, showing the weight at its lower end for supporting the head in upright position.

It is found very desirable to produce a 45 form of animated toy in which the head member may be moved about upon the body member and to construct such a toy so that it is very strong and durable, and one which will successfully withstand the heavy shocks and banging about which children's toys are 50 subjected to, without being broken; and the following is a detailed description of one means by which such results may be accomplished:—

With reference to the drawing, 10 designates the hollow bulbous body member of a toy which may be made in any suitable or

desired shaped such as egg-shape, spherical or the like, and this body member is preferably formed in halves, each half being pressed into the desired form and constructed of any suitable sheet material, preferably celluloid, the meeting edges 11 and 12 of these halves being designed to fit one within the other, which edges are connected together preferably by cement. In the bottom of this body member, I have mounted a weight 13 preferably of lead of the desired size and of a shape preferably to fit the inner circumference of the body, and I have provided a cap member 14 adapted to fit over the weight 13, the same being provided with a flange 15 which may be connected to the inner surface of the body member by cement or otherwise, for the purpose of fixing or securing the weight in position therein 75

The upper portion of this body member is provided with a hole 16.

Mounted upon this body member is a head member 17 which may be of any suitable shape or size and to represent any desired 80 object, the same being adapted to be supported upon the outer surface of the body member and to roll or move about thereon.

In order to movably support this head upon the body member I have provided a 85 rod 18 with its upper end 19 extending through an opening 20 in the upper wall of the head member, this opening being shown as provided with inturned lips or flanges 21 for engaging and supporting the upper end 90 of the rod, the inturned flanges being so formed as to provide a tapering opening for the purpose of receiving cement by which to more securely fasten the end of the rod to the upper wall of the head member. 95

This rod preferably extends down through the head member to fit tightly in a hole 22 in the lower wall thereof and to extend through the enlarged hole 16 in the upper surface of the body down into said body in 100 which it loosely fits, the lower end 23 of this rod being provided with a weight 24 which is adapted to swing like a pendulum within the hollow body as the head member is agitated, serving to return the head member to 105 upright position after having been moved therefrom.

On this rod, within the body, I have fixed a collar 25 which may serve to limit the separating movement of the head member relative to the body member. 110

By forming the member of this toy of cel-

luloid various colors may be employed in its construction which render the same handsome and attractive in appearance.

By forming the body portion in a spherical shape and mounting a weight 13 therein this body may be rolled about upon any surface, its rolling movement imparting a relative movement of the head member in the opposite direction, which is due to the swinging of the weight on the rod 23 within the body member thus giving to the toy a life-like action which renders it very attractive and interesting.

Then by mounting the comparatively heavy weight 13 in the bottom of the body portion a gradually reducing rocking motion is imparted to the body portion as it is returning to its normally upright position.

The device is extremely strong and durable in construction and handsome and attractive in appearance.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. An animated toy comprising a bulbous body member having a head member mounted to roll about upon its upper surface, a balancing rod fixed in said head member and extending into said body to swing freely therein, said rod being weighted on its lower end to return said head member when moved from upright position, and a weight also in said body for returning it with its head member to upright position when moved therefrom.

2. An animated toy comprising a bulbous body member having a head member mounted to roll about upon its upper surface, a balancing rod having its upper end secured in the upper wall of said head member and extending down therethrough into said body member the lower end being weighted and arranged to swing freely therein to automatically return said head member when moved from upright position, a collar on said rod within said body member, and a weight secured to the base portion of the body to return the same with its head when moved from upright position.

In testimony whereof I affix my signature.

ARTHUR V. DA COSTA.
